UNITED STATES PATENT OFFICE.

ROBERT CASTELBERG, OF WASHINGTON, DISTRICT OF COLUMBIA.

DESIGN FOR A SPOON.

SPECIFICATION forming part of Design No. 32,725, dated May 29, 1900.

Application filed May 3, 1900. Serial No. 15,424. Term of patent 3½ years.

To all whom it may concern:

Be it known that I, ROBERT CASTELBERG, a citizen of the United States, residing in Washington, District of Columbia, have invented and produced a new and original Design for Spoons, of which the following is a specification, reference being had to the accompanying drawing, showing a part thereof.

My invention is a design for spoons and is illustrated in the accompanying drawing, which is a front elevation of a spoon embodying the design as a unitary article.

The bowl of the spoon presents an illustration of the Capitol at Washington. The handle presents a beading on each edge. At the outer end of the handle is represented in bas-relief an Egyptian simitar, beneath which is the head of an Egyptian sphinx. Next below the head of the sphinx is represented a

star, beneath which is represented an illustration of an Egyptian fez, located above the representation of a camel. At the point where the handle joins the bowl is represented an illustration of a pyramid.

The leading feature of the design is the handle with the representation as described.

Having thus described my invention, what I claim, and desire to secure by Letters Patent, is—

The design for a spoon as herein shown and described.

In testimony whereof I have signed my name to this application in the presence of two subscribing witnesses.

ROBERT CASTELBERG.

Witnesses:

CHARLES M. OWENS,

GEORGE M. MATTINGLY.
